UNITED STATES PATENT OFFICE.

MICHAEL E. SOMAN, OF NEW YORK, N. Y., ASSIGNOR TO DAVID KLEBANOFF AND SAMUEL GROSSMAN, COPARTNERS TRADING AS KLEBANOFF AND GROSSMAN, OF NEW YORK, N. Y.

DESIGN FOR A FINGER RING.

Application filed January 23, 1926. Serial No. 16,245. Term of patent 3½ years.

To all whom it may concern:

Be it known that I, MICHAEL E. SOMAN, a citizen of the United States of America, residing at the city, county, and State of New York, have invented a new, original, and ornamental Design for Finger Rings, of which the following is a specification, reference being had to the accompanying drawings, forming part thereof.

Fig. 1 is a side elevation of a ring embodying the new design;

Fig. 2 is a top plan view thereof; and
Fig. 3 is an edge view thereof.

I claim:

The ornamental design for a finger ring as shown.

In witness whereof I have signed this specification this 12th day of January, 1926.

MICHAEL E. SOMAN.
